UNITED STATES PATENT OFFICE.

CHARLES J. NISSLER, OF BRADY, TEXAS.

SIGNALING DEVICE FOR AUTOMOBILES.

1,270,434.

Specification of Letters Patent. Patented June 25, 1918.

Application filed November 24, 1915. Serial No. 63,260.

To all whom it may concern:

Be it known that I, CHARLES J. NISSLER, a citizen of the United States, residing at Brady, in the county of McCulloch, State of Texas, have invented certain new and useful Improvements in Signaling Devices for Automobiles; and I do hereby declare the following to be a full, clear, and exact description of the invention, such as will enable others skilled in the art to which it appertains to make and use the same.

The present invention is directed to improvements in signaling devices for automobiles, and has for its object to so construct a device of this character that the driver can indicate to a following vehicle the direction in which he is about to turn.

A further object of the invention is to provide a device of this type which is exceedingly simple in construction, and one which can be easily and quickly attached to the frame of the usual wind shield.

A still further object is to provide a manually operated signal capable of being quickly operated and held in its operative position, whereby the driver can give his entire attention to the steering wheel.

It is customary that a driver, about to turn, extends the hand from the vehicle to indicate the direction in which the vehicle is to be turned, but in instances where the curtains of the vehicle are in use this practice is found to be unhandy, and it is to overcome this objection that the present invention has been perfected.

With these and other objects in view, this invention resides in the novel features of construction, formation, combination and arrangement of parts to be hereinafter more fully described, claimed and illustrated in the accompanying drawing, in which:

Figure 1 is a rear elevation of the devices.

Fig. 2 is a sectional view on line 2—2 of Fig. 1.

Fig. 3 is a sectional view on line 3—3 of Fig. 1.

Fig. 4 is a fragmentary perspective view of the tube.

The signal consists of a tube 1 which is disposed horizontally on the usual wind shield frame 2, and is attached thereto by the clamps 3. The ends of the tube extend slightly beyond the sides of the frame 2, and are provided with longitudinal slots 4, the outer ends of which are open. Slidably mounted in the tube 1 are rods 5, to the outer ends of which are fixed metal signal plates 6, which may be painted any desired color, whereby the plates will represent flags.

The inner ends of the rods have fixed thereto bolts 7 which project through the aligned slots 8 formed in the tube 1, and have engaged on the projected ends nuts 9, said nuts being provided with finger pieces 10, so that the nuts can be adjusted to hold the rods from sliding accidentally, said finger pieces also serving as means whereby the rods can be moved outwardly or inwardly. When the rods are in their inoperative position the plates 6 will engage in the slots 4, and at which time the nuts are in binding engagement with the tube, thus holding the rods against accidental movement.

Assuming that a driver desired to turn to the right, it is only necessary to grasp the nut adjacent the right hand side of the shield frame, and give the same a partial rotation so as to remove it from binding engagement with the tube 1, whereupon the associated rod 5 may be moved outwardly so as to display the connected plate to the driver of an oncoming vehicle. Thus it will be seen that it will be necessary for the driver to remove only one hand from the steering wheel to actuate the signal, which being quickly accomplished, the hand can be returned to the wheel, while the signal remains displayed.

What is claimed is:—

A direction indicator for vehicles comprising a tube adapted to be secured transversely to the wind shield of a vehicle and having its ends projecting beyond the sides of said wind shield and having slots in the lowermost portions thereof, the outer ends of said slots being open, said tube being also

provided with other slots arranged in a different plane from the first named slots, a rod 5
slidable in each end of said tube and having a signal plate at its outer end normally engaged in the adjacent open ended slot, a bolt carried by the inner end of each of said rods and extended through one of the second named slots toward the driver's seat of the

vehicle, and means on said bolt for securing the rod in adjusted position. 10

In testimony whereof, I affix my signature, in the presence of two witnesses.

CHARLES J. NISSLER.
